OWL FIGURINE

Stig Hedman, Gavle, Sweden, and Torkel Nilson, Redmond, Wash.; said Hedman assignor to said Nilson

Filed Aug. 29, 1972, Ser. No. 284,637

Term of patent 3½ years

Int. Cl. D11—02

U.S. Cl. D29—23 B

FIG. 1 is a front elevational view of an owl figurine showing our new design;

FIG. 2 is a side elevational view thereof; and

FIG. 3 is a vertical sectional view in the axial plane transverse of FIG. 1.

We claim:

The ornamental design for an owl figurine, as shown.
